UNITED STATES PATENT OFFICE.

CHARLES EDWARD HAVILAND, OF LIMOGES, FRANCE.

DESIGN FOR A DISH OR SIMILAR ARTICLE.

SPECIFICATION forming part of Design No. 32,870, dated June 26, 1900.

Application filed May 31, 1900. Serial No. 18,685. Term of patent 7 years.

To all whom it may concern:

Be it known that I, CHARLES EDWARD HAVILAND, a citizen of the United States, residing at Limoges, in the Republic of France, have 5 invented and produced a new and original Design for a Dish or Similar Article, of which the following is a specification, reference being had to the accompanying drawings, forming a part thereof, and in which—

10 Figure 1 is a top view of a dish bearing and incorporating my design. Fig. 2 is a side elevation, partly in section, of same, the section being on the dotted line 2 2 of Fig. 1; and Fig. 3 is a detached horizontal section of a portion 15 of same on the dotted line 3 3 of Fig. 2.

The leading features of my design consist of the shape of the body of the dish and the ornamental configuration thereon, substantially as shown.

20 In the drawings, A designates the body of the dish, which body has the outwardly-flar-

ing scalloped upper edges B and the downwardly-curved side surfaces C, converging inwardly to and terminating at the ornate scalloped base D. The upper surfaces of the upper edges or rim of the dish bear the ornate scalloped scroll configuration E, which is slightly in relief, and the outer surfaces of the base D bear a substantially-similar ornate scroll configuration F. At the points intermediate the scallops of the scroll configuration E are the downwardly-extending raised surfaces or ribs G.

25 What I claim is—

The design for a dish or similar article, substantially as shown and described.

Signed at Paris, in the Republic of France, this 17th day of May, A. D. 1900.

CHARLES EDWARD HAVILAND.
